UNITED STATES PATENT OFFICE.

THORVALD J. PETERSEN, OF NEW YORK, N. Y., ASSIGNOR TO THE GLOBE LIGHTING FIXTURE MANUFACTURING COMPANY, OF BROOKLYN, NEW YORK, A COPARTNERSHIP.

DESIGN FOR A CHANDELIER.

Application filed May 21, 1928. Serial No. 26,792. Term of patent 3½ years.

To all whom it may concern:

Be it known that I, THORVALD J. PETERSEN, a citizen of the United States, residing at New York city, in the county of New York and State of New York, have invented a new, original, and ornamental Design for a Chandelier, of which the following is a

specification, reference being had to the accompanying drawing, forming part hereof, in which the figure is a perspective view, showing my new design.

I claim:

The ornamental design for a chandelier, as shown.

THORVALD J. PETERSEN.
